DESIGN FOR A SHOE

Paul M. Seigel, Chicago, Ill., assignor to Valley
Shoe Corporation, St. Louis, Mo., a corporation of Missouri

Application April 18, 1935, Serial No. 56,446

Term of patent 3½ years

To all whom it may concern:

Be it known that I, Paul M. Seigel, a citizen of the United States, residing at the city of Chicago, county of Cook, State of Illinois, have invented a new, original, and ornamental Design for a Shoe, of which the following is a specification, reference being made to the accompanying drawing, forming a part thereof, in which Figure 1 is a plan view and Figure 2 is a perspective view of a shoe embodying my design.

I claim—

The ornamental design for a shoe, substantially as shown.

PAUL M. SEIGEL.
